[57] CLAIM

The ornamental design for a single whirlpool bath display, as shown.

DESCRIPTION

FIG. 1 is a perspective of the single whirlpool bath display, showing my new design;

FIG. 2 is a top plan view thereof;

FIG. 3 is a front elevational view thereof;

FIG. 4 is a left side elevational view thereof; and

FIG. 5 is a right side elevational view thereof.

The rear of the claimed article is substantially plain and unornamented.

FIG. 1

FIG. 2

FIG. 3

FIG. 4

FIG. 5
